Primary Examiner — Antoine D Davis(74) *Attorney, Agent, or Firm* — Hanley, Flight & Zimmerman, LLC(57) **CLAIM**

The ornamental design for a “diagnostic analyzer,” as shown and described.

DESCRIPTION

FIG. 1 is a front left perspective view of a diagnostic analyzer.

FIG. 2 is a front view of the analyzer of FIG. 1.

FIG. 3 is a rear view of the analyzer of FIG. 1.

FIG. 4 is a right side view of the analyzer of FIG. 1.

FIG. 5 is a left side view of the analyzer of FIG. 1.

FIG. 6 is a top view of the analyzer of FIG. 1.

FIG. 7 is a bottom view of the analyzer of FIG. 1.

FIG. 8 is a front left perspective view of a diagnostic analyzer.

FIG. 9 is a front view of the analyzer of FIG. 8.

FIG. 10 is a rear view of the analyzer of FIG. 8.

FIG. 11 is a right side view of the analyzer of FIG. 8.

FIG. 12 is a left side view of the analyzer of FIG. 8.

FIG. 13 is a top view of the analyzer of FIG. 8; and,

FIG. 14 is a bottom view of the analyzer of FIG. 8.
